GIUSEPPE BURNENGO, OF GENOA ITALY

REGULATING TRANSFORMER

Application filed May 3, 1926, Serial No. 106,526, and in Italy May 5, 1925.

The present invention relates to improvements in and relating to static transformers of the type which are regulated through the motion of a member of magnetic material, 5 said motion producing a variation of the quantity of magnetic flux linking with windings of the circuits, thus obtaining a regulation of the transformer. The present invention more particularly consists in 10 the arrangement of the windings on the transformer with regard to their mutual relationship or to their position relatively to said variable regulating member. The invention further consists in the arrangement 15 of an auto-transformer adapted to vary the voltage. The invention also consists in a transformer arrangement in which the loss of voltage in the secondary circuit is partly compensated for by an arrangement of the 20 windings.

In the accompanying drawings are shown by way of example various forms of the invention.

Fig. 1 shows schematically one form of 25 winding arrangement which is shown in position on a core in Fig. 2;

Figs. 3 and 4 show other connections of the windings of Fig. 2;

Figs. 5 and 6 show two courses of the 30 magnetic flux in accordance with the positions of the movable magnetic member of the device shown in Fig. 7;

Fig. 8 shows a further arrangement of cores and windings; and

Figs. 9, 10 and 11 show respectively a side elevation, end elevation and plan of a practical embodiment of the invention.

The present invention provides means 40 whereby the impedance of reactance coils may be varied and whereby the mutual inductance between the various coils of auto and other transformers may be adjusted in accordance with well-known requirements.

Referring particularly to Fig. 1, there is 45 shown a set of windings connected in series in which the current may be supplied between the points 11 and 12 while the desired working current is taken from the points 11 and 13 or vice versa. Each of 50 the windings 14, 15, 16 and 17 is wound

in a direction corresponding to the direction of one of the windings 18, 19, 20 and 21. The latter windings are suitably interposed between the former as shown in Fig. 2. Both the primary and the secondary windings are composed of four coils, two with more turns than the other two and arranged in such a manner that the two spools of the primary windings with the more turns are in direct inductive relation to the spools 60 of the secondary with the less turns and vice versa, in order that there may be less voltage drop in the secondary. The movable shunt member 22 is shown as transversely movable between the coil-receiving legs of a 65 closed magnetic core.

The two primary windings with more turns induce more flux in the secondary sections consisting of a less number of turns of 70 small wire. The larger number of turns of thin wire are arranged in inductive relation to the primary windings of a small number of turns as, for instance, at the right hand of Fig. 2 in order to allow of the obtaining, in the secondary working circuit, of a compensated flux and a compensator flux. The 75 auto transformer is reversible in its operations, i. e., it may be supplied with a low voltage and a high voltage drawn therefrom, or vice versa. If, instead of arranging the windings as shown in Fig. 3, they are connected as shown in Fig. 4, a transformer for raising or lowering the voltage is obtained.

Figs. 5 and 6 show the two extreme conditions of the magnetic flux in the core. First, when the movable member of the core is completely inserted and second, when it is completely removed. In the first case, the voltage in the secondary is of a minimum 80 value but never zero. In the second case, parallel lines of flux flow through the movable member 22 and are of the same amount. This results in a diminution of the resistance in all of the windings whereby the 85 voltages of the secondary will increase in accordance with the ratio of the turns.

Fig. 7 shows schematically the arrangement of the core of Fig. 2 with the movable member 22 between the parts 23 and 24 90

of the core, while in Fig. 8 the movable member is shown as divided into two parts, 22' and 22'', which may have similar or dissimilar movements in respect to each other, so that the proportions of the induced voltages in the various windings can be adjusted to suit various external conditions.

A practical embodiment of the invention is shown in Figs. 9, 10 and 11, wherein *a a* represents the coil receiving legs of a closed circuit core of which *b b* are the end members. The windings are shown at *c, d, e, and f*. Each winding is composed of two coils such as has been explained in connection with Fig. 3. Between the inner surfaces *g* and *h* of the core legs there is arranged, for longitudinal movement, a core member *k* through which passes a screw threaded rod *i* provided at one end with a handwheel *l*. The rod is threaded into a member *m* rigidly supported by the core and moves freely in the block *k* but is prevented from longitudinal movement therein by means of suitable washers. Thus, by rotating the rod by means of the hand wheel, the block may be moved from the position shown in full lines in Fig. 10, where it is between the core legs, to a position where it is completely removed from between these parts of the core. It is displaced in the direction of the arrow *m* when being drawn between the core parts. When in the closed position the hand wheel assumes the position indicated by dotted lines at *l'*. Binding posts for the various windings are indicated at *o*.

I claim:

A variable static transformer comprising a core having a pair of parallel legs, a movable magnetic member disposed between said parallel legs, a primary winding and a secondary winding on each leg, each winding on each leg comprising a major section and a minor section, the major and minor sections of each winding being arranged in close inductive relation to the minor and major sections, respectively, of the other winding.

In testimony whereof I affix my signature.
GIUSEPPE BURNENGO.
